UNITED STATES PATENT OFFICE.

FRANK K. TOVEY, OF PITTSBURGH, PENNSYLVANIA, ASSIGNOR TO UNION CAP MANUFACTURING COMPANY, OF PITTSBURGH, PENNSYLVANIA, A COPARTNERSHIP COMPOSED OF HIMSELF AND EDWARD J. EAGAN.

LAMP HOLDER FOR MINERS' CAPS.

Application filed November 13, 1924. Serial No. 749,675.

To all whom it may concern:

Be it known that I, FRANK K. Tovey, a citizen of the United States, residing at Pittsburgh, in the county of Allegheny and 5 State of Pennsylvania, have invented certain new and useful Improvements in Lamp Holders for Miners' Caps, of which the following is a specification.

My invention relates to improvements in 10 lamp brackets or holders for miners' caps. It has for its object to provide means for supporting and positively holding the lamp in position on the usual standard Z-shaped frame in front of the cap, to prevent displacement or loosening in various positions.

In the use of miners' lamps, and especially 15 with those utilizing acetylene, the weight of the lamp is apt to cause undesirable swinging, tilting, or displacement during 20 the work of mining and the varying positions of the user. In my invention, I provide for attachment by its hook of a standard lamp on the usual front bracket in the ordinary way. The present improvement 25 consists of an improved friction socket secured in such a position as to receive the point of the hook, and also to exert a certain degree of outward tension as the hook is inserted with resulting binding friction 30 and prevention of lateral movement towards either side.

Referring to the drawings, showing a preferred embodiment of the invention;

Fig. 1 is a perspective view of a miner's 35 cap provided with my invention;

Fig. 2 is a central vertical section through 40 the front bracket, showing the lamp in place;

Fig. 3 is a plan view of the bracket;

Fig. 4 is an upper front view of the bracket;

Fig. 5 is a vertical section on the line 45 V—V of Fig. 4, without the supporting frame; and

Fig. 6 is a perspective detail view of the frictional retaining socket.

In the drawings, the usual miner's cap 2 is shown having the visor 3 with the standard lamp supporting frame or bracket 4. 50 In the present case, this bracket is made of stiff sole leather shaped to form the middle front panel and the top and bottom oppositely extending attaching flange portions 5 and 6, riveted to the cap and visor

respectively. Secured by rivets around the 55 upper front corner of frame 4 is the thin sheet metal angle plate 7, the middle of which is formed into a rounded outwardly bulging rib 8 having the central slot 9. Said slot is formed to just receive the 60 hooked stem 10 of the lamp 11, and to snugly embrace it to prevent lateral movement. The shank of the hook bears against the face of the bracket immediately below the slot at the point 12, as shown in Fig. 5. 65

Ordinarily, the point of the hook is merely inserted in a receiving hole 13 through the top of the frame 4 or through a separately attached metal plate secured on the 70 top of the flange, having upper lateral confining flanges and a downwardly extending tubular socket.

In my invention, I form a friction socket 75 pressed from sheet metal and riveted to the under side of the bracket, as shown. It consists of an upper flat bearing and securing flange 14 having terminal eyes 15, 15, for rivet connection with the under side of the upper flat portion 5 of frame 4.

The middle portion 16 of the friction 80 socket extends downwardly and rearwardly from the flange 14, forming a groove 17 between the bent around sides or cheeks 18, 18, as in Fig. 6. The rearward and downward slope of the inner face of the groove 85 and its cross sectional area conform approximately to the direction and shape of the end portion of hook 10 of the lamp. The socket is so located with relation to the front portion of angle plate 7 that when the hook 90 is inserted in hole 13, its shank portion 19 will bear against the middle portion 12 as the terminal portion 20 enters the groove 17 of the friction socket. By reason of the relative location of the friction socket, it 95 exerts a slightly spreading resistance to the hook, tending to distend it as it is inserted, so that it bears with binding friction against the socket and also against plate 7 at 12. When thus in position, as in Fig. 2, with the shank 100 firmly in place in groove 9 of rib 8 and the hook terminal between the cheeks 18, the lamp will be positively held against accidental movement or removal. The efficiency 105 of the device is due to the holding friction exerted by the socket against the resistance of the front bearing 12, with the lateral engagement with the sides of the hook in

groove 9, hole 13, and between the cheeks 18.

By such construction, I avoid the necessity of using supplemental wires or other holding devices on the body of the lamp, so that it is positively, continuously and safely held by the hook alone during the varying positions and strains of use, until removed.

What I claim is:

- 10 A supporting bracket for a miner's lamp consisting of a bracket frame secured to the

cap and visor respectively having a top flat portion provided with a hook hole, a forwardly bulging slotted front bearing plate, and a rearwardly inclined open back 15 grooved friction socket for the hook terminal secured to the bracket frame below and in register with the hook hole.

In testimony whereof I hereunto affix my signature.

FRANK K. TOVEY.
